(57) **CLAIM**

The ornamental design for a lamp, as shown and described.

DESCRIPTION

FIG. 1 is a perspective view of a lamp showing a first embodiment of my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof;

FIG. 7 is a bottom plan view thereof;

FIG. 8 is a reduced exploded perspective view thereof; and, FIG. 9 is a perspective view of a second embodiment thereof, the only difference from the disclosure of the first embodiment residing in the showing of one element broken away, which is understood to indicate that the vertical dimension of that element is an unclaimed length; and,

FIG. 10 is a perspective view of a third embodiment thereof, the only difference from the disclosure of the first embodiment residing in the showing of the narrow vertical stem at the bottom in broken lines.

The broken line disclosure in the views is understood to represent portions of the article in which the claimed design is embodied, but which form no part of the claimed design.
